J. Gregory Chrisman(57) **CLAIM**

The ornamental design for a cabin for telescopic lifter, as shown and described.

DESCRIPTION

FIG. 1 is a front-left side-top perspective view of a cabin for telescopic lifter, showing the new design;

FIG. 2 is a top view thereof;

FIG. 3 is a back-left side-top perspective view thereof;

FIG. 4 is a left side view thereof;

FIG. 5 is a front view thereof; and,

FIG. 6 is a back view thereof.

The broken lines depict portions of the cabin for telescopic lifter that form no part of the claimed design.
